CLAIM

The ornamental design for a shoe as shown and described.

DESCRIPTION

FIG. 1 is a top, front perspective view of a shoe upper, showing an embodiment of my new design.

FIG. 2 is a front elevation view of the shoe upper illustrated in FIG. 1.

FIG. 3 is a rear elevation view of the shoe upper illustrated in FIG. 1.

FIG. 4 is a first side elevation view of the shoe upper illustrated in FIG. 1.

FIG. 5 is a second side elevation view of the shoe upper illustrated in FIG. 1; and,

FIG. 6 is a top plan view of the shoe upper illustrated in FIG. 1.

The broken lines in the Figures illustrate portions of the shoe that form no part of the claimed design.

1 Claim, 6 Drawing Sheets
